(57) **CLAIM**

An ornamental design for a tether device, as shown and described.

DESCRIPTION

FIG. 1 is a perspective view of a tether device showing our new design;

FIG. 2 is a front elevation view thereof;

FIG. 3 is a rear elevation view thereof;

FIG. 4 is a right side view thereof;

FIG. 5 is a left side view thereof;

FIG. 6 is a top plan view thereof;

FIG. 7 is a bottom plan view thereof; and,

FIG. 8 is another perspective view of the tether device.

The broken line showing hands is included for the purpose of illustrating environment and forms no part of the claimed design.
